by

UNITED STATES PATENT OFFICE.

HARRY R. CLARKE, OF EAST ORANGE, NEW JERSEY, ASSIGNOR TO WESTERN ELECTRIC COMPANY, INCORPORATED, OF NEW YORK, N. Y., A CORPORATION OF NEW YORK.

SUPPORT FOR HEAD TELEPHONE RECEIVERS.

Application filed December 8, 1922. Serial No. 605,625.

To all whom it may concern:

Be it known that I, HARRY R. CLARKE, a citizen of the United States residing at East Orange, in the county of Essex, State 5 of New Jersey, have invented certain new and useful Improvements in Supports for Head Telephone Receivers, of which the following is a full, clear, concise, and exact description.

10 This invention relates to telephone apparatus and particularly to supports for head telephone receivers.

The object of the invention is to provide an improved construction for head telephone 15 receiver sets, whereby they will readily adapt themselves to the head and ears of the user and will be free from moving parts or joints likely to catch the hair of the user or cause other discomforts when placed in or removed 20 from position of use.

In accordance with the general features 25 of this invention the adjustable hinged or movable connection between the head band and the receiver support is covered or concealed by a rounded smooth member which prevents abrasions of the skin or catching in the hair of the user. More specifically, the invention contemplates the use of a thimble or casing secured to the head band and 30 within which the receiver support is swiveled thereby covering movable parts likely to exert a pinching or an abrading action.

Fig. 1 a head set embodying the features 35 of this invention.

Fig. 2 is a cross section of the swivel joint used as a connection between the head band and the receiver support.

Fig. 3 is a transverse section through the 40 swivel joint at 3—3.

Fig. 4 is a transverse section through the swivel joint at 4—4.

Fig. 5 is an exploded view of the swivel 45 joint.

A wire band 6 preferably made in one piece is provided at one end with a small rubber block 7 pivotally supported on the right angle portions 21—21. The block 7 may be provided with perforation 24 within 50 which the portions 21—21 terminate, and are preferably joined by means of the sleeve 22 soldered thereto to prevent their disengagement from the block 7. The block 7 serves as a pad presenting a large supporting sur-

face which permits the receiver being held 55 snugly against the ear without undue pressure of the wire band on the head. The other end of the wire band 6 is provided with a right angle bend 8. A receiver unit 9 is pivotally supported by studs 11 in a fork 10 comprising a yoke 23 and a rod 12 rigidly 60 attached thereto. The upper end of the rod 12 is provided with a projection 13 and a reduced portion 14. Rotatably associated with rod 12 is a thimble 15 provided with an internal shoulder 16. A split washer 17 65 engaging the rod 12 at its reduced portion seats against the shoulder 16 of the thimble 15. The washer 17 and the thimble 15 mutually lock each other in position. A screw 18 having symmetrically disposed slots 19 70 for receiving the wires 6, is placed between them and the thimble 15 which is internally threaded, is then screwed over the screw 18 and the end 8 of wires 6 thereby rotatably 75 securing the receiver fork 10 to the head band. A projection 20 on screw 18 is adapted upon a predetermined movement of rod 12 to engage a projection 13 thereon and thus prevent further rotation.

When the block 7 is not required the wire 80 of the head band may be looped at this end in the usual manner and the ends of the rod terminated in the bend 8 where they will be held securely in the thimble 15 by means of screw 8.

The invention claimed is:

1. A support for telephone receivers comprising a receiver fork, a thimble rotatably connected to said receiver fork, means engaging said receiver fork to prevent the removal of said thimble, said means and said thimble mutually locking each other, and means rigidly securing said thimble to said head band.

2. A support for telephone receivers comprising a head band, a receiver fork, and a swivel connection therebetween comprising a thimble surrounding adjacent ends of said head band and said fork, said thimble being rigidly secured to said band and rotatably secured to said receiver fork.

3. In a telephone head set, a swivel connection comprising coaxially disposed relative rotatable members, sector shaped projections on said members adapted to engage 100 each other to limit their relative movement 105

and a thimble secured on one of said members entirely surrounding said projections.

4. In a telephone head set, a swivel connection comprising a hollow cylindrical thimble, a receiver support inserted in one end of said thimble, means within said thimble to rotatably secure said support thereto, a head band inserted in the opposite end of said thimble, and a closure for one end of said thimble adapted to rigidly secure said head band thereto.

5. A head set comprising a head band, a receiver fork and a swivel connection there-

for comprising a cup, a rod connected to said fork and projecting through the bottom of 15 said cup, a split washer straddling a recess in said rod and supported on a shoulder within said cup, and a longitudinally slotted screw at one end of said head band co-operating with the cup for holding the receiver fork freely attached to said head band.

In witness whereof, I hereunto subscribe my name this 28th day of November, A. D. 1922.

HARRY R. CLARKE.
